METHOD AND APPARATUS FOR PICKLING
METAL COILS

Agnes J. Reeves Greer, Morgantown, W. Va.

Application January 5, 1939, Serial No. 249,484

15 Claims. (Cl. 148—8)

The invention relates to apparatus and method for pickling coils of metal and more particularly to certain improvements upon the general type of pickling machines disclosed in my prior Patent No. 2,091,921, issued August 31, 1937; Shoemaker Patent No. 2,120,843, issued June 14, 1938; and my prior application Serial No. 230,304, for Recoiler, filed September 16, 1938; and the present application is a continuation in part of my co-pending application for improvement in Pickling machines, Serial No. 203,507, filed April 22, 1938.

Machines of the general character referred to provide for the pickling of coils of metal supported upon mandrels which are rotated as they are progressed through the pickling and washing tanks whereby the coils are in turn rotated by the mandrels.

It is necessary that the multiplicity of convolutions of each coil be separated from each other while immersed in the pickling solution in order to prevent dark spots or streaks from being formed upon the metal. To this end the back spinner disclosed and claimed in the Shoemaker patent above referred to, and later the recoiler disclosed and claimed in my prior application above referred to, were produced for the purpose of back spinning each coil prior to its introduction into the pickling tank in order to separate all of the convolutions from each other in the pendent portions of the coil.

It has also been found desirable to open up or separate the convolutions of the coil while immersed in the washing tanks in order to more readily wash all of the pickling acid from the surface of the metal.

It has also been found by experience that even though the convolutions of a coil are sufficiently separated or opened up by the back spinner or recoiler before the coil enters the pickling or washing bath, the continuous rotation of the coil forwardly upon the mandrel tends to wind or close up the convolutions of the coil so that before the coil has passed entirely through the bath the convolutions thereof will touch each other at some points, particularly toward the outer portion of the coil, resulting in the formation of dark spots or streaks upon the surface of the metal where two convolutions contact each other in the pickling bath, and preventing a thorough washing of the metal where the convolutions contact each other in the washing bath.

It has also been found that in some cases it may be desirable to rotate the coil forwardly or backwardly upon the mandrel at a greater speed than that at which the mandrel shaft is rotating,

in order to facilitate the pickling or washing of the coil.

It is therefore an object of the present invention to provide means for preventing the coils from becoming tightly wound while they are progressing through the pickling or washing baths.

Another object is to provide a machine of the character referred to including a coil supporting mandrel comprising a shaft with means for continuously rotating said shaft to move it forwardly upon a track, and a sleeve rotatably mounted upon the shaft with means for rotating the sleeve relative to the shaft whereby the sleeve may be rotated either forwardly or backwardly at any desired or necessary speed relative to the speed of rotation of the shaft.

A further object is to provide a mandrel of the character referred to and means for rotating the mandrel and moving it in a forward direction upon a track, there being a sprocket or gear upon the sleeve, and driving means co-operating therewith, for rotating the sleeve in the same direction with the shaft upon a fixed track throughout a portion of its travel and driving means co-operating with the sprocket or gear for rotating the sleeve in a direction opposite to the rotation of the shaft during another portion of its travel.

A still further object of the improvement is to provide means for suspending a coil of metal in a pickling or washing bath and continuously advancing the coil through the bath, and alternately rotating the coil clockwise and anti-clockwise around its axis as it is continuously advanced through the bath, so as to prevent the coil from winding upon itself to such an extent that the convolutions of the coil will contact each other in the bath.

Still another object of the improvement is to provide means for suspending a coil of metal upon a mandrel in a pickling or washing bath and advancing the mandrel to move the coil through the bath and rotating the coil upon the mandrel in a direction opposite to the direction in which the convolutions of the coil are wound about the center of the coil to open up the convolutions of the coil.

The above objects together with others which will be apparent from the drawings and the following description, or which may be later referred to, may be attained by constructing and operating the improved pickling machine in the manner illustrated in the accompanying drawings, in which:

- Figure 1 is an elevation of the recoiler, charging device and entrance end of the pickling tank;
- Fig. 2, a top plan view of the mechanism shown in Fig. 1;
- 5 Fig. 3, a sectional elevation of the pickling tank showing the mechanism for back spinning and forwardly spinning the coils upon the mandrels as the coils pass through the pickling bath.
- Fig. 4, a top plan view of the mechanism shown 10 in Fig. 3;
- Fig. 5, a sectional elevation of the first washing tank showing the mechanism for spinning the coils in either direction upon the mandrels, as the coils pass through the first washing bath;
- 15 Fig. 6, a top plan view of the mechanism shown in Fig. 5;
- Fig. 7, a sectional elevation of the second washing tank with the mechanism for spinning the coils therein, and the discharging mechanism 20 for conveying the coils away from the machine;
- Fig. 8, a plan view of the mechanism shown in Fig. 7;
- Fig. 9, an enlarged elevation of the mechanism 25 for back spinning the coils in the tanks;
- Fig. 10, a plan view of the mechanism shown in Fig. 9;
- Fig. 11, an enlarged, transverse section through the pickling tank and the back spinning mechanism;
- 30 Fig. 12, a section on the line 12—12, Fig. 11;
- Fig. 13, an enlarged fragmentary sectional view of one end portion of the improved mandrel;
- Fig. 14, a detail view of a coil showing the method of wiring the end thereof;
- 35 Fig. 15, a fragmentary detail sectional elevation of one of the improved transfer arms; and
- Fig. 16, an enlarged plan view of a modified form of the mechanism for back spinning or forwardly spinning the coils in the tanks.
- 40 Similar numerals refer to similar parts throughout the drawings.
- The pickling machine generally may be of the same construction as disclosed in the patents above referred to with the additions and improvements forming the present invention, and 45 may comprise the combined recoiler and back spinner indicated generally at A, which may be of the construction and arrangement disclosed in my prior application for Recoiler, Serial No. 230,304, the coil charging mechanism illustrated generally at B, the pickling tank C, the transfer mechanism D, for transferring the mandrels and coils from the pickling tank C to the first washing tank E, the coil transfer mechanism F 50 for transferring the mandrels and coils from the first washing tank E to the second washing tank G, the coil discharge mechanism H for discharging the coils from the second washing tank and placing them upon the up-ender I, and the gravity conveyor J for conveying the coils away 55 from the machine, all of said parts being arranged in the sequence enumerated.
- The recoiler and back spinner shown generally at A in Figs. 1 and 2 may be of the same construction and operation as disclosed in detail in my recoiler application above referred to and includes feeding and brake mechanism indicated generally at 15 for feeding the front end of a coil to the recoiler drum 16, upon which the coil is 60 recoiled and back spun to produce a metal coil as indicated at 17 which may be conveyed upon the cradle 18 to a point from which it may be discharged upon the gravity coil storage platform 19.
- 65 At this point the outer end of the coil may be 70 wired to the next adjacent convolution, this being done for the purpose of preventing the exterior of the coil from becoming materially larger in diameter as the coil is passed through the machine.
- The coil loading mechanism indicated generally at B includes the inclined rails 20 at which point the improved mandrel, or roll forming a part of the present invention, is inserted into each coil, the mandrel being supported upon the rails 20 and in turn supporting the coil thereon in the manner disclosed in detail in the prior patents above referred to.
- The improved mandrel comprises a shaft 21 having a roller 22 fixed near each end thereof and adapted to travel upon the corresponding rails which are associated with the tanks as will be later described.
- A sprocket wheel 23 may be fixed upon each end portion of the mandrel shaft 21 and is adapted to travel upon the corresponding toothed tracks associated with the tanks as will be later described.
- The pickling tank C may be of suitable length, depending upon the speed at which the coils 25 are advanced therethrough, to obtain a proper pickling of each coil in its passage through the pickling tank.
- Rails 24 may be mounted at the top of the tank adjacent to each side wall thereof forming a 30 track upon which the mandrels may be rotated throughout the length of the tank, the rollers 22 on the mandrel shaft traveling upon said rails whereby the coils suspended from the mandrels are preferably partially submerged in the 35 pickling bath and may be rotated therein as will be later described. The sprocket wheels 23 on the mandrel shaft are adapted to travel upon the corresponding toothed tracks 25 which may be fixed to any stationary portion of the machine 40 adjacent to the pickling tank, such as the rails 24 as illustrated.
- The upper side of each of the sprocket wheels 23 is adapted to be engaged by an endless drive 45 chain 26 located under sprockets 27 at opposite ends of the pickling tank, and preferably running beneath the longitudinal chain guides as disclosed in detail in the Shoemaker patent which insure engagement of the drive chains with the sprocket wheels 23.
- The drive chains 26 may be continuously driven in unison by means of the gearing indicated at 29 and the motor 30, which drives the chains in the direction of the arrows shown in the drawings, the mandrel shaft 21 being positively rotated in a forward direction by the cooperation of the chains 26, sprocket wheels 23, and toothed tracks 25.
- A mandrel sleeve 31 forms a part of the mandrel and is rotatably mounted upon the mandrel shaft 21, between the rollers 22 thereon, and bushings 32 are preferably located around the mandrel shaft and within the sleeve, as best shown in Fig. 13 of the drawings.
- This mandrel sleeve may be provided with the 60 enlarged middle portion 33 having the spaced annular grooves 34 therein for adjustably mounting the flange plates 35 to accommodate coils of different widths, as illustrated and described in detail in Patent No. 2,120,843, above referred to.
- Near one end of the mandrel sleeve 31 is fixed a sprocket wheel 36 adapted to ride upon a toothed track 37 located adjacent to the side walls of the pickling tank and interrupted at one or more points between the ends of the tank, as 75

illustrated in Figs. 9 and 10 of the drawings, for a purpose to be later described.

If desired, a section of tube 38, of considerably larger diameter than the mandrel sleeve, may 5 be located around the mandrel sleeve and within the open center of the coil as shown in Figs. 11 and 12.

Thus, with the coil supported by the mandrel sleeve, as the mandrel is driven forwardly upon 10 the rails 24 by means of the drive chains 26, the sprockets 23 engaging the toothed tracks 25 will cause the mandrel shaft to be positively rotated forwardly, and during the time that the sprocket 36 is in contact with the toothed track 37 the 15 mandrel sleeve, and with it the coil 17, will be rotated in the same direction and at the same speed as the mandrel shaft 21 as indicated by the curved arrow in Fig. 3.

As above stated, even though the convolutions 20 of the coil are properly separated or opened up before the coil is mounted upon the mandrel and charged into the pickling tank, a continual rotation of the mandrel and coil in this direction while passing through the tank causes the coil 25 to wind upon itself. This action is produced by the inner convolutions of the coil being enlarged with each rotation while the outer circumference of the coil remains the same size, thus, resulting 30 in the outer convolutions of the coil being closed or moved into contact with each other at many points within the acid, producing dark spots or streaks upon the surface of the metal at the points of contact.

In order to overcome this objection the invention 35 contemplates means for rotating the mandrel sleeve, and the coil carried thereby, in the reverse direction for a portion of its travel, so as to again open up or separate the convolutions of the coil before they become wound together 40 to such extent as to contact with one another in the bath.

For this purpose, the mechanism indicated generally at K and shown in detail in Figs. 9, 10 and 11 may be located at a point along the tank C 45 where the toothed track 25 is interrupted. This mechanism may be of any length necessary to accomplish the purpose, and if desired may extend along the entire length of the tank, and may be located at any suitable position relative 50 to the entrance and discharge ends of the tank, or, if desired, two or more of these devices may be located at various points along the length of the tank.

This mechanism may be driven by the motor 55 39, located above one side of the tank C upon a suitable frame indicated at 40. Suitable reduction gearing may be located in a housing 41 interposed between the motor and the drive shaft 42 upon which is mounted a sprocket wheel 43 60 adapted to drive the sprocket chain 44 in the direction of the arrows shown in Fig. 9, in order to rotate the mandrel sleeve 31, and the coil carried thereby, in a direction opposite to that in which the mandrel shaft 21 is rotated.

65 The chain 44 first passes down around and under an idler sprocket wheel 45 mounted upon an arm 46 adjustable upon the center 47 in order to take up any slack in the chain, and then forwardly and around the sprocket wheel 48, journaled upon the frame 40 at a point adjacent to one end of the break in the toothed track 37.

After passing around the sprocket wheel 48 the chain 44 runs rearwardly in a substantially horizontal direction beneath the rigid chain guide 49, arranged to hold the chain down in contact 70

with the sprocket wheel 36 upon the mandrel sleeve, as the same is moved forward beneath the chain.

At the rear of this chain guide the chain passes upwardly around the sprocket wheel 50, mounted 5 upon the frame 40 adjacent to the other end of the break in the toothed track 37, and then upward and around the drive sprocket 43.

It will thus be seen that as the mandrel is moved forwardly, advancing the coil through the acid 10 in the pickling tank, the shaft of the mandrel will be continuously rotated in a forward direction while the mandrel sleeve upon which the coil is supported is alternately rotated forward and then backward, rotating the coil therewith 15 and thus preventing the convolutions of the coil from being tightly wound so as to contact with each other while the coil is in the acid.

By referring to Fig. 12, it will be seen that as the coil is rotated forwardly, or in the direction 20 in which the convolutions of the coil are wound about the center of the coil, the action of the rotating mandrel sleeve 27 upon the inner convolutions of the coil will cause these inner convolutions to be enlarged, forcing the same outward and closing the spaces between convolutions. 25

However, when the direction of rotation of the mandrel sleeve is reversed, that is in a direction opposite to the direction in which the convolutions 30 of the coil are wound about the center of the coil, then these inner convolutions will be decreased in diameter, pulling them away from the outer convolutions of the coil, so as to open up 35 the convolutions of the coil.

It should be understood that the chain 46 may be driven at any desired speed so as to rotate the mandrel sleeve backward at any speed desired or necessary, relative to the speed of forward rotation of the mandrel shaft. 40

With this arrangement the speed of the backward rotation of the sleeve may, if desired, be equal to the speed of the forward rotation of the mandrel shaft or may be faster or slower than the speed of rotation of the shaft. 45

In cases where the coils are extremely heavy, or where two or more coils may be placed upon each mandrel it may be desirable to construct the reversing mechanism in the manner shown in Fig. 16, in which means is provided for driving 50 both ends of the mandrel sleeve 31a.

For this purpose the reversing mechanism may include the driving motor 39a located above one side of the tank upon the frame 40a and connected through the reduction gearing 41a to the 55 drive shaft 42a which may extend entirely across the tank being provided with the spaced sprocket wheels 43a and 43b which drive the sprocket chains 44a and 44b on opposite sides of the tank. The chains 44a and 44b may be the same as the 60 chain 44 shown in Figs. 9 and 10, the chain 44a passing under the sprocket wheel 45a then around the sprocket wheel 48a and then running rearwardly and then around the sprocket wheel 50a.

The chain 44b in the same manner passes down 65 around and under the sprocket wheel 45b then forwardly and around the sprocket wheel 48b and then rearwardly and around the sprocket wheel 50b.

The mandrel sleeve 31a is provided near opposite ends with the sprocket wheels 36a and 36b, which are engaged by the chains 44a and 44b, respectively, so as to positively drive the sleeve from both ends. 70

After leaving the reversing mechanism the 75

mandrel may be moved forwardly throughout the length of the pickling tank, the mandrel sleeve 31 being rotated forwardly at the same speed as the mandrel shaft 21, this being accomplished by engagement of the sprocket wheel 36 of the sleeve with the toothed track 37.

However, it may be desirable in many cases to rotate the coil forwardly at a different speed from that of the mandrel shaft. For this purpose a mechanism indicated generally at L, and being exactly the same in construction and operation as the reversing mechanism K excepting that it is oppositely disposed thereto, may be located on the pickling tank at any suitable point relative to the reversing mechanism K for the purpose of rotating the mandrel sleeve, and with it the coil forwardly at a different speed from the speed of rotation of the mandrel shaft.

Although it may be preferable to rotate the coil forward at a higher speed than the speed of the mandrel shaft, it should be understood that the mechanism indicated generally at L may be operated at any desired speed either slower or faster than the mandrel shaft.

Although only one reversing machine and one forward spinning machine is illustrated in the pickling tank, it should be understood that two or more of each or either of these machines may be located at suitable positions relative to the pickling tank and the reversing mechanism K may be located either before or after the forward spinning mechanism L, the purpose being to reverse the direction of rotation of the coil and spin the same faster or slower than the speed of the mandrel shaft at the point or points which may be found necessary in order to produce the desired results.

Between the discharge end of the pickling tank C and the entrance end of the first water tank E is located the transfer mechanism indicated generally at D. This transfer mechanism includes a shaft 51 journaled in bearings 52, and provided with a spaced pair of coil transfer arms 53, each having a coil engaging hook 54 at its free end.

The shaft 51 may be connected through suitable gearing indicated generally at 55, to a motor or other driving means arranged to be automatically operated, as disclosed in my prior patent, as each mandrel is received in the hooks 54.

The hooks are substantially the same as illustrated and disclosed in the above mentioned Patent No. 2,120,843, except that the track portion 56 of each hook, including the toothed track 57 which engages the sprockets 23 of the mandrel shaft, is concaved instead of being straight, so as to retard the movement of the mandrel as it rolls down the tracks of the hooks to be deposited in the first water tank.

The first water tank 58, comprising a part of the first washing unit E, is located directly beyond the acid tank and is preferably of greater depth than the acid tank, as shown in the drawings, so that the entire coil may be submerged in the water as it is passed through the tank in order to wash the acid from the coil.

For this purpose the washing tank 58 may be of greater width than the acid tank so as to receive the entire length of each mandrel therein as best shown in Fig. 6.

Rails 59 may be supported inside of the tank 58 adjacent to the side walls thereof, preferably at a point considerably below the top of the tank to receive the flanged rollers 22 of the mandrels 75 in such position that the entire coils may be

submerged within the water when the coils are received in the tank 58, as shown in Fig. 5.

A pair of driving chains 60, similar to the chains 26, are provided for moving the mandrels with the coils supported thereon through the water tank 58 by engagement with the sprockets 23 upon the mandrel shaft.

It should be understood that these sprockets 23 upon the mandrel shaft are adapted to ride upon toothed tracks 61 similar in every respect to the toothed tracks 25 which are associated with the pickling tank, and that a toothed track 62, similar in every respect to the toothed track 31, is provided for engagement with the sprocket wheel 36 upon each mandrel sleeve.

The toothed track 62 may be interrupted at the points where the reversing mechanism K' and forward spinning mechanism L' are located for engagement with the sprockets 36 upon the mandrel sleeve, these mechanisms being identically the same as those above described which are associated with the pickling tank and being adapted for rotating the mandrel sleeve, either in reverse or forwardly, independently of the mandrel shaft and at any desired speed relative thereto.

The drive chains 60 are operated in the same manner as the chains 26 in the pickling tank, being located over the sprocket wheels 63 mounted upon shafts 64 journaled in bearings 65 located near opposite ends of the tank 58 and around the curved chain guides 66 which guide the lower strand of each chain into engagement with the sprockets 23 of the mandrel shafts. Gearing 67 is provided, together with a motor 68, for driving both of the chains 60 in unison.

The coil transfer mechanism indicated generally at F may be of identically the same construction and operation as the coil transfer mechanism D and is adapted to transfer the mandrels with the coils thereon from the first washing tank 58 to the second washing tank 69, which forms a part of the second washing unit G.

The second washing unit is provided with drive chains 70, rails 71 and toothed tracks 72 and 73 constructed and arranged identically the same as the corresponding drive chains, rails and toothed tracks in the pickling tank and first washing tank, and may also be provided with the reversing mechanism K₂ and forward spinning mechanism L₂ constructed and operating in the same manner as the corresponding devices K, K', L and L' above described.

If desired, this second washing tank may contain hot water as is customary in the second washing units of pickling machines, and, for the purpose of preventing rusting of the metal for some time after it has been pickled and washed, soluble oil may be mixed with the hot water in this second washing tank so as to place a thin film of oil upon the surface of the metal of each coil when it is removed from the machine.

If it is desired to store the pickled coils for some considerable time, a layer of mineral oil 65 may be placed in the second washing tank upon the solution of water and soluble oil, the soluble oil causing the mineral oil to adhere to the surface of the metal.

As each coil reaches the discharge end of the second washing tank, it will enter the coil discharge mechanism H, the transfer arms 74 of which may be constructed and operated in the manner above described regarding the other transfer arms of the machine.

As the mandrel shaft is received in these transfer arms the same will be operated to transfer the mandrel and coil, depositing the coil upon the cradle 75 and the mandrel upon the bracket plates 76 so that the same may be removed from the coil.

The pickled and washed coil is then transferred by the up-endor I onto the gravity conveyor J by means of which the coil is carried away from 10 the discharge end of the machine.

It should be understood that although a combined recoller and back spinner is illustrated and described for opening up the convolutions of the coil before it is placed upon the mandrel and 15 advanced through the several baths, it may be possible in many instances to pass the coil through the baths without first opening up the convolutions thereof, since the back spinning mechanism illustrated and described herein may 20 sufficiently open up the convolutions of the coil to produce a satisfactory pickling and washing thereof as it is advanced through the machine.

I claim:

1. Apparatus for pickling, washing or treating 25 a coil of metal, including a tank containing liquid, a mandrel upon which the coil is supported, said mandrel comprising a shaft and a sleeve rotatably mounted upon the shaft and of sufficient length to support the coil, a track adjacent to the side walls of the tank upon which the mandrel shaft is supported, means for rotating the mandrel shaft in a direction to move it forwardly along the track, and means for 30 rotating the mandrel sleeve in the reverse direction whereby the coil is rotated in the reverse direction to that of the mandrel shaft as said coil is moved forwardly through the liquid.

2. Apparatus for pickling, washing or treating 40 a coil of metal, including a tank containing liquid, a mandrel upon which the coil is supported, said mandrel comprising a shaft and a sleeve rotatably mounted upon the shaft and of sufficient length to support the coil, a track adjacent to the side walls of the tank upon which the mandrel shaft is supported, means for rotating the mandrel shaft in a direction to move it forwardly along the track, and means for rotating the mandrel sleeve in the same direction as the shaft during a portion of its travel and for 45 rotating the mandrel sleeve in the reverse direction during another portion of its travel, whereby the coil is alternately rotated in opposite directions as it is moved forwardly through the liquid.

3. Apparatus for pickling, washing or treating 50 a coil of metal, including a tank containing liquid, a mandrel upon which the coil is supported, said mandrel comprising a shaft and a sleeve rotatably mounted upon the shaft and of sufficient length to support the coil, a track adjacent to the side walls of the tank upon which the mandrel shaft is supported, means for rotating the mandrel shaft in a direction to move it forwardly along the track, a sprocket upon the 55 mandrel sleeve, and a toothed track at a point along the tank in the path of the sprocket for engaging the upper side of the sprocket for rotating the mandrel sleeve in the reverse direction to the shaft so that the coil is rotated in the reverse direction to that of the mandrel shaft as said coil is moved forwardly through the liquid.

4. Apparatus for pickling, washing or treating 60 a coil of metal, including a tank containing liquid, a mandrel upon which the coil is supported, said mandrel comprising a shaft and a

sleeve rotatably mounted upon the shaft and of sufficient length to support the coil, a track adjacent to the side walls of the tank upon which the mandrel shaft is supported, means for rotating the mandrel shaft in a direction to move it forwardly along the track, a sprocket upon the 65 mandrel sleeve, and a moving toothed track at a point along the tank in the path of the sprocket for engaging the sprocket and means for moving said moving toothed track in a direction and at a speed for rotating the mandrel sleeve in the reverse direction to the shaft so that the coil is rotated in the reverse direction to that of the mandrel shaft as said coil is moved forwardly through the liquid.

5. Apparatus for pickling, washing or treating 70 a coil of metal, including a tank containing liquid, a mandrel upon which the coil is supported, said mandrel comprising a shaft and a sleeve rotatably mounted upon the shaft and of sufficient length to support the coil, a track adjacent to the side walls of the tank upon which the mandrel shaft is supported, means for rotating the mandrel shaft in a direction to move it forwardly along the track, a sprocket upon the 75 mandrel sleeve, a toothed track at a point along the tank in the path of the sprocket for engaging the under side of the sprocket for rotating the mandrel sleeve in the same direction as the shaft and a second toothed track at another point along the tank in the path of the sprocket for engaging the upper side of the sprocket for rotating the mandrel sleeve in the reverse direction, so that the coil is alternately rotated in opposite directions as it is moved forwardly through the liquid.

6. Apparatus for pickling, washing or treating 80 a coil of metal, including a tank containing liquid, a mandrel upon which the coil is supported, said mandrel comprising a shaft and a sleeve rotatably mounted upon the shaft and of sufficient length to support the coil, a track adjacent to the side walls of the tank upon which the mandrel shaft is supported, means for rotating the mandrel shaft in a direction to move it forwardly along the track, a sprocket upon the mandrel sleeve, a fixed toothed track at a point along the tank in the path of the sprocket for engaging the lower side of the sprocket for rotating the mandrel sleeve in the same direction 85 as the shaft and a moving toothed track at another point along the tank in the path of the sprocket for engaging the sprocket and means for moving said moving toothed track in a direction and at a speed for rotating the mandrel sleeve in reverse direction, so that the coil is alternately rotated in opposite directions as it is moved forwardly through the liquid.

7. Apparatus for pickling, washing or treating 90 a coil of metal, including a tank containing liquid, a mandrel upon which the coil is supported, said mandrel comprising a shaft and a sleeve rotatably mounted upon the shaft and of sufficient length to support the coil, a track adjacent to the side walls of the tank upon which the mandrel shaft is supported, means for rotating the mandrel shaft in a direction to move it forwardly along the track, a sprocket upon the mandrel sleeve, a fixed toothed track at a point along the tank for engaging the under side of the 95 sprocket for rotating the mandrel sleeve in the same direction as the shaft and a moving toothed track at another point along the tank for engaging the upper side of the sprocket and means for moving said moving toothed track in a direction 100

75

tion and at a speed for rotating the mandrel sleeve in the reverse direction, so that the coil is alternately rotated in opposite directions as it is moved forwardly through the liquid.

- 5 8. Apparatus for pickling, washing or treating a coil of metal, including a tank containing liquid, a track adjacent to the side walls of the tank, a mandrel for supporting the coil, said mandrel comprising a shaft supported upon the track and 10 a sleeve rotatably mounted upon the shaft and of sufficient length to support the coil, means for rotating the mandrel shaft to move it along the track, and means for simultaneously independently rotating the mandrel sleeve upon the shaft.
- 15 9. The method of pickling, washing or treating a coil of metal supported on a mandrel with its pendent portion only submerged in a bath, which includes advancing the coil continuously through the bath and rotating the coil around its axis 20 alternately clockwise and anti-clockwise as it is continuously advancing through the bath.

10. The method of pickling, washing or treating a coil of metal internally supported and suspended in a bath which includes advancing the 25 coil continuously through the bath and rotating the coil around its axis alternately clockwise and anti-clockwise as it is continuously advancing through the bath.

11. The method of pickling, washing or treating a coil of metal supported upon a mandrel in a bath in such position that forward rotation of the coil tends to close up the convolutions of the coil, continuously advancing the coil forward through the bath and rotating the coil around 35 its axis so that the top of the coil moves in a direction opposite to the direction in which the coil is advancing and opposite to the direction in which the convolutions of the coil are wound about the center of the coil to open up the convolutions of the coil.

12. Apparatus for pickling, washing or treating a coil of metal, including a tank containing liquid, a mandrel upon which the coil is supported, said mandrel comprising a shaft and a sleeve rotatably mounted upon the shaft and of sufficient length to support the coil, a track adjacent to the side walls of the tank upon which the mandrel shaft is supported, means for moving the mandrel shaft forwardly along the track, and

means for rotating the mandrel sleeve upon the shaft in a direction to rotate the coil so that the top of the coil moves in a direction opposite to the movement of the mandrel shaft as it is progressed through the liquid.

5 13. Apparatus for pickling, washing or treating a coil of metal, including a tank containing liquid, a mandrel upon which the coil is supported, said mandrel comprising a shaft and a sleeve rotatably mounted upon the shaft and of sufficient 10 length to support the coil, a track adjacent to the side walls of the tank upon which the mandrel shaft is supported, means for moving the mandrel shaft forwardly along the track, and means for rotating the mandrel sleeve upon the 15 shaft in one direction during a portion of its travel and in the reverse direction during another portion of its travel so that the coil is alternately rotated in opposite directions as it is progressed through the liquid.

20 14. Apparatus for pickling, washing or treating a coil of metal, including a tank containing liquid, a mandrel upon which the coil is supported, said mandrel comprising a shaft and a sleeve rotatably mounted upon the shaft and of sufficient 25 length to support the coil, a track adjacent to the side walls of the tank upon which the mandrel shaft is supported, means for moving the mandrel shaft forwardly along the track, a sprocket upon the mandrel sleeve, movable toothed tracks at 30 points along the tank for engaging the upper side of the sprocket for rotating the mandrel sleeve upon the shaft, and means for moving said movable toothed tracks in opposite directions and at various speeds so that the coil may be alternately 35 rotated in opposite directions and at any desired speed relative to the mandrel shaft as said coil is moved forwardly through the liquid.

40 15. Apparatus for pickling, washing, or treating a coil of metal including a tank containing liquid, a track adjacent to the side walls of the tank, a mandrel for supporting the coil, said mandrel comprising a shaft supported by the track and a sleeve rotatably mounted upon the shaft and of sufficient length to support the coil, 45 means for moving the mandrel shaft along the track, and means for simultaneously, independently rotating the mandrel sleeve upon the shaft.
